UNITED STATES PATENT OFFICE

2,367,913

TRANSFER MECHANISM FOR CIGAR
MACHINES

Henry H. Wheeler, Bellerose, N. Y., assignor to
International Cigar Machinery Company, a
corporation of New Jersey

Original application January 5, 1938, Serial No.
183,405. Divided and this application January
1, 1942, Serial No. 425,319

6 Claims. (Cl. 131—38)

This invention relates to cigar machines, and more particularly to transfer mechanism for transferring bunches and cigars to and from the several manipulating mechanisms of the machine. This invention constitutes a division of my co-pending application Serial No. 183,405 filed January 5, 1938, for High speed cigar machines, now Patent No. 2,316,828, issued April 20, 1943.

It has been found that in sprocket and chain operated types of transfers heretofore used in cigar machines for the transfer of bunches to the wrapping station, and of cigars from the wrapping station, the chains which were used to operate the transfers have a tendency to stretch and they, therefore, play an important part in the accuracy of the grippers of the transfers. Obviously, if after continued use a chain were to stretch, the point at which the grippers became operative would not be true, and they would either release or grip prior or subsequent to their predetermined point of operation. Also, due to the open construction of the transfers considerable dust and dirt and grit accumulate thereon, and have an appreciable effect upon the wear thereof and the efficiency, as well as giving them an untidy appearance.

According to the present invention, marked improvements have been made in the transfer structure since the chains and sprockets mentioned above have been eliminated, and replaced by simple shafts and suitable pinions thereon; and all driving mechanism has been enclosed so that there is little or no danger that dirt, dust or grit will accumulate on the transfer and, furthermore, exceptional accuracy necessarily results because of the elimination of mechanism which was responsible for this defect.

The invention also consists in the provision of a novel type of elongated article transfer means wherein all of the operating structure is enclosed, thereby preventing the accumulation of dust and dirt on the transfer operating mechanism.

It is an additional object to provide a new and improved cigar and bunch transfer, having totally enclosed operating parts, and gears for insuring parallel motion of the article holding means thereof in place of sprockets and chains, which results in more accurate control and permits enclosure of the operating mechanism with a minimum of bulk.

It has been found advisable to prevent waste of wrappers which are to be applied to bunches in the rolling machines in the event that a bunch is not fed to the rolling machine for association with the wrapper and hence means have been

provided for interrupting the wrapper feed whenever a bunch is not located to receive a wrapper.

It is a further purpose of the invention to associate with the bunch transfer mechanism a device which cooperates with the wrapper feed to prevent the feed of wrappers to the wrapping station whenever the absence of a bunch is detected in the bunch transfer.

A further object of this invention is to provide an electrically controlled means to prevent transfer of wrappers from the die to carrier when there is no bunch transferred to the wrapping device, thereby preventing waste of expensive wrappers.

15 It is a further object of the invention to provide means for maintaining the grippers of the improved cigar and bunch transfers in such a position that cigars and bunches are always held in a horizontal position.

20 It is also an object of the invention to provide means for adjusting the limits of travel of the bunch and cigar transfer devices, and to also provide improved means for preventing travel of these transfers beyond said limits.

25 It is a further object of the invention to provide a detecting means located on the bunch transfer which determines the presence or absence of a bunch in said transfer.

It is a further object of the invention to provide detecting means for determining the presence or absence of a bunch in a bunch transfer and means associated therewith for preventing feed of wrappers to the cigar rolling mechanism whenever it is indicated that a bunch is not present in said transfer to receive said wrappers.

With these and other objects, not specifically mentioned, in view, the invention consists of certain constructions and combinations which will be set forth more in detail in the specification and then described more fully in the claims hereunto appended.

40 In the accompanying drawings, which form a part of this specification, and in which like characters of reference indicate the same or like elements:

Figure 1 is a front elevation of my improved cigar rolling machine;

Figure 2 is a side elevation of the same, on lines 2—2 of Figure 1;

45 Figure 3 is a side elevation on line 3—3 of Figure 1 showing the carrier portion of the bunch transfer, with a cigar bunch in position;

Figure 3a is a side elevation similar to Figure 3, but with transfer empty;

50 Figure 3b is a side elevation similar to Figure

3a, showing specific details of the transfer head;

Figure 4 is a side elevation of the bunch and cigar transfer assembly provided with transfers which transfer bunches and cigars from one manipulating part of the machine to another;

Figure 5 is a sectional end elevation of the same, on lines 5-5 of Figure 4;

Figure 6 is a sectional end elevation of the same, on lines 6-6 of Figure 4;

Figure 7 is a top view from line 7-7 of Figure 4;

Figure 8 is a sectional plan view on line 8-8 of Figure 5;

Figure 9 is an end elevation of the bunch transfer portion of Figure 5 showing a modified form of bunch transfer; and

Figure 10 is a sectional plan view on line 10-10 of Figure 9.

Referring to Figures 1 and 2, the improved cigar rolling machine consists of a bunch transfer 11 which picks up the finished bunches B from a bunch making machine, which may be either a long or a short filler bunch machine (not shown) and carries them along the path indicated by the arrow 13 in Figure 2 to the rolling device 14 in which a cigar wrapper cut on the die 15 by the cutting rollers 16 and brought into position by the wrapper carrier 17, guided by cams 18 and 19, is wound around the bunch. The tuck end of the wrapper is placed on the bunch by the tuck needle 23 in the conventional manner, and its flag end, to which a dab of paste has been applied by the paster 21 on its way to the wrapping device, is expelled from the carrier by a blow-off 22, which may be of the type shown in United States Patent No. 2,215,490 granted September 24, 1940, to Henry H. Wheeler. A cigar transfer 23 then transports the wrapped cigar C along path 24 (Figure 1) to reroller 25 in which the wrapper is smoothed and the softened cigar, after being trimmed to size, by knives (not shown) and treated by a knurler (not shown) is discharged from the cradle 26 to be collected and given a finishing touch in the hand knurler 27 by the operator.

The construction of the rolling device 14 in the embodiment herein illustrated is similar to that disclosed in co-pending application, Serial No. 107,792 filed October 27, 1936, by James P. Durning, now Patent No. 2,290,171, issued July 21, 1942; while the wrapper carrier 17 may be of the type described in my co-pending application above referred to. The paster 21 may be similar in construction to that shown in the United States Patent No. 2,012,149, issued August 20, 1935, to Henry H. Wheeler, and therefore, further detailed description of these mechanisms is believed unnecessary.

In the embodiment selected for illustration, the machine is driven by a motor 28, controlled by a starting switch 30, through a clutch 29 which is electrically controlled by conveniently located hand switches 31, 32 and by foot pedal switches 33 and 34, and limit switch 167, the former actuated by the operator of the rolling machine and the latter by the operator of the bunch machine (not shown). For convenience in installing and subsequent check up, a jogging or inching switch 35 is provided, by which the machine can be advanced step by step through increments of a cycle, for checking on the timing, and for making other adjustments of the different parts whenever necessary. This mechanism forms no part of this

invention and, therefore, further description and disclosure is deemed unnecessary.

The operating units of the machine are mounted on a base plate 36 suitably supported by side frames 37, 38 and by an end frame 39 which are completely covered by metal sheeting 40. The side frames 37, 38 support a cam shaft 41 and fulcrum shafts 42, 43, 44, 45 and 46, the inner ends of shafts 42 and 43 being supported in housings 47 and 48, respectively, attached to base plate 36. The side frame 38 also carries the bracket 49 on which the motor 28 is mounted. The metal sheeting which encloses the front and sides of the machine preferably is removably mounted in order, both to enhance the appearance thereof, and provide accessibility to the working parts for repairs, etc.

The cam shaft 41 has a worm wheel 50 driven by a worm 51 on a hollow shaft 52 supported in the housing 53 of wheel 50. The shaft 52 is connected by a coupling 54 of conventional design, to the hollow shaft 55 of the clutch 29, a solid shaft 56, passing through shafts 52 and 55, being coupled to a shaft 57 supported by the clutch housing 29 and carrying a pulley 58 driven by a belt 59 from the pulley 60 of the motor 28.

On the bunch transfer 11 is mounted a balance arm 150, (Figures 1 and 2) held by a spring 151 in its up-position 150' in which, on the swinging 30 of the transfer along path 13 (Figure 2), it engages the nose 152 of an arm 153 affixed to a vertical shaft 154 extending from pedestal 141. In its up-position, the lower end of the balance arm 150 rests on a plunger 155 (Figure 3a, and 35 3b) carrying a toggle joint 156 which is then in its down-position with transfer fingers 157 located apart for the entry of a cigar bunch B. In entering the fingers 157, the bunch B trips the toggle 156, thereby raising the plunger 155 and 40 turning the balance arm 150 into its down-position in which it clears the nose 152 when the transfer arm 11 is moved through its prescribed arc. In the "down" or bunch delivery position 45 the tail portion of arm 150 engages stationary member 22a on blow-off 22 (Figure 1) which depresses plunger 155 and opens jaws 151 to release a bunch held therebetween.

When at any time the transfer fails to pick up 50 a bunch, the toggle 156 is not tripped, balance arm 150 remains in its up-position 150', and shaft 154 will be rotated through a given angle by the arm 153. On the lower end of shaft 154 is attached a switch 158 which is held open by the shaft 154 when the arm 153 is in its normal undisturbed position. If, however, as stated above, the shaft 154 is moved by the balance arm 150, switch 158 closes contact 159 which is connected in series with a timing or limit switch 160, and with a solenoid 161, the limit switch 60 being closed by the raising of a spring-tensioned roller 162 through its engagement with a cam piece 163, attached to the periphery of cam 82. The solenoid 161 when energized at the proper moment by the coaction of switches 158 and 160, 65 pulls a lever 164 pivoted on a stud in bracket 165 into the path of the lifter lever 125 actuating the rod 127 which operates the lifter head 128 and transfers the cut wrapper from the die 15 to the wrapper carrier 17, thereby preventing spring 126 from raising the same to effect such transfer.

Referring to Figure 2, it will be seen that when 70 wrapper carrier 17 is in wrapper receiving position over a die 15, head 128 is lifted to deliver

the wrapper to the carrier. At this time suction is cut off in head 128 and created in carrier 17, as set forth in the application referred to above. The upward movement of head 128 is effected by a spring 126 fast to one arm of cam lever 125 connected at one end to rod 127, and provided with a cam follower 124 on its other end tracking a cam 85 which lowers the head after delivery of a wrapper.

Thus, there is provided an automatic inspecting mechanism which detects the presence or absence of bunches in the transfer device. By means of this device the feed of wrappers to the rolling or wrapping mechanism is so controlled that a wrapper cannot be transferred from the cutting die for transfer to the wrapping station unless a bunch has indicated its presence in the bunch transfer member. Obviously, this makes possible an appreciable savings in the wrappers which are an expensive item in cigar manufacture, since it prevents the waste of the wrappers fed to the rolling mechanism whenever a bunch is not transferred thereto for association with the particular wrapper. This structure, therefore, adds much to the efficiency and practicality of the machine, and tends to lower the cost of production of the cigars made thereon.

The cam 82 carries a cam piece 163, the latter opening a limit switch 167, through engagement with a follower 168 carried by said switch and thereby stops the machine at the end of each cycle of the machine. The limit switch 167 is shunted by a circuit containing the foot switches 33 and 34 in series so that the latter can start the machine from zero (provided the manual switches 31 and 32 are closed), but, if released during a cycle, cannot stop it until the cycle is completed.

The transfer mechanism of this invention, while readily useable on any cigar machine, is especially well adapted for use on a machine such as shown in my co-pending application, above referred to. Due to the fact that the bunch and cigar transfer mechanism 11 and 23, respectively, are mounted to operate in a single pedestal 141 located on the table of the cigar rolling machine, there is no necessity for changing and adjusting the bunch transfer structure except for the gripper heads since they have been designed to function with either a long or a short filler bunch forming device. This has also been brought about by the fact that the point of transfer of the bunches from the cigar bunch shaping units of the short filler unit, and the forming device of a long filler machine will occupy the same relation with respect to transfer arm 11 regardless of the combination of units used, whereby the arm 11 remains of constant length in either combination. Neither the short nor the long filler bunch forming mechanisms are shown since they form no part of this invention.

The construction of the bunch and cigar transfer, which carries the cigar bunches from the bunch machine to the wrapper applying device of the rolling machine, and after wrapping transfers the cigar to the reroller, is shown in Figures 4 to 10.

The rack 149, which is actuated by cam lever 148 on shaft 43 and guided by a flanged wheel 263, engages a gear 264 on a shaft 265 supported in pedestal 141. The guide wheel 263 is mounted on an eccentric stud 266, thus permitting accurate adjustment of the tooth engagement. The shaft 265 passes through the hub of a bevel gear 267 which is held fast to pedestal 141 by a

bolt 268. On shaft 265 is turnably mounted the flanged hub of the hollow arm 11 in which is journaled a shaft 269 carrying at its ends bevel gears 270 and 271. Shaft 265 has a crank arm 5 272 which is detachably connected to arm 11 by means of a spring-tensioned, ball-top plunger 273 fitting into a stell socket 274 inserted into the hub flange of arm 11. The gear 270 at the inner end of shaft 269 meshes with the fixed gear 261, and the gear 271 at its outer end engages with a gear 275 on a horizontal shaft 276 journaled in arm 11 and carrying the bunch holder 277. The turning of the gear 270, as it rolls on the stationary gear 267, rotates the horizontal shaft 276 by an angle equal to that through which the arm 11 is moved by the crank 272, thus keeping the bunch holder 277 in its vertical position at all times and at any angle of arm 11. Therefore, when a bunch or cigar is to be lifted or delivered, the grippers are always properly positioned for correct operation. The arm 11 has two adjustable stop screws 278, one of which engages with a stop 279 in either position 11 or 11' of the transfer arm, corresponding to the spaced positions B, B' (Figure 4) of the cigar bunch, in the bunch machine turret and in the wrapping device, respectively. In case the stroke of rack 149 is made slightly greater than required for the correct adjustment of the screws 278, the plunger 273 leaves the socket 274 at the end of each stroke and snaps back at the beginning of the next, and no damage is done to the mechanism.

The rack 149 which is actuated by link 280 on cam lever 139 is kept in lateral alignment by a guide block 281 fitted into pedestal 141 and fastened to base 12, and is held in tooth engagement with a gear 282 on a shaft 283 by a flanged wheel 284 on an eccentric stud 285. The shaft 283 passes through the hub of a bevel gear 286, held stationary in pedestal 141 by a screw 287, and carries the transfer arm 23, the stop screws 288 of which engage with a stop 289 at its end position, corresponding to the positions C and C' (Figure 5) of the cigar in the wrapping device and in the reroller, respectively. The arm 23 has the shafts 290 and 291 with the bevel gears 292, 293 and 294, the horizontal shaft 291 having a cross stud 295 loose in its fork end 296 carrying the cigar holder jaw 297 which is held in tension by a spring 298 pressing against pins 299 and 300, and which is opened and closed against a stationary cigar holder plate 301 attached to fork 296, by a pin 302 in a collar 303 fast on stud 295, the said pin being controlled by a cam piece 304 attached to arm 23.

Under some conditions it may be necessary to swing a bunch through 90° in transferring it from one position to another. For example, when the transfer is used in a short filler bunch combination (not shown), the cigar bunch B is turned through a right angle while being transferred from the bunch machine to the rolling machine. The horizontal shaft 276 of the transfer arm 11 carries a bevel gear 305 (Figures 9 and 10) fixed to said shaft and meshing with a gear 306 on the holder 277 which in this case is loose on a vertical core 307 clamped to the end of shaft 276. The tooth ratio of gears 305 and 306 is so chosen that gear 306 normally moves one-quarter revolution as gear 305 turns through an arc equal to that between the extreme positions B—B' of transfer arm 11, i. e., the arc indicated by arrow 13 in Figure 4. As described hereinabove spring overthrow plunger 273 operates to prevent movement of gear 306 greater than 90° if for any rea-

son rack 149 swings arm 11 beyond its set limits of movement.

The shaft 154 of arm 153 is held in position through friction produced by a spring 308 pressing on the clamp 309 carrying the switch 158 which when turned by arm 153, connects the insulated terminals on contact piece 159. The nose 152 is held against a projection on arm 153 by a spring 310, permitting the balance arm 150 to continue its forward motion by turning the nose out of the way after the switch 159 has contacted, and to reengage the same on its return motion so as to turn arm 153 back into neutral position.

It is to be noted that the transfer mechanism for conveying bunches and cigars to and from the various operating stations of the machine are substantially entirely enclosed and are extremely simple in construction and operation. This makes possible a more efficient transfer than known heretofore, and insures greater wearing qualities for the parts making up their organization, since dirt, dust and possible abrasives, which are often present in tobacco, cannot get into the working parts of the transfer. Furthermore, the safety of an operator is greatly increased due to the enclosing of all parts so that it is impossible for her to come into contact with said parts. Also, the cleaning of this mechanism can readily be effected without danger of clogging any of the parts since it merely requires a wiping of plain, rounded exterior surfaces.

The mechanism above described may be varied in construction within the scope of the claims hereunto appended, since the particular device selected to illustrate the invention is but one of many possible concrete embodiments thereof. The invention is not, therefore, to be restricted to the precise details of the structure shown and described.

What is claimed is:

1. In a cigar machine, a rolling station, a wrapper cutting die, a wrapper carrier, means for delivering wrappers from said die to said carrier, a transfer for conveying bunches to said station, mechanism for incapacitating said delivery means, including a control arm yieldably mounted on said transfer, and means coacting with said arm to prevent the operation of said delivery means whenever no bunch is carried by said transfer.
2. Mechanism for interrupting the feed of wrappers to a wrapping unit of a cigar machine, comprising a wrapper carrier constructed and arranged to deliver wrappers to said unit, a device for feeding wrappers to said carrier, a bunch transfer, grippers mounted on said transfer, toggle members controlling said grippers, a pin connected to said members, an arm on said transfer, means yieldably mounting said arm on said transfer to engage said pin, and means located for engagement by said arm to incapacitate said device and prevent delivery of a wrapper to said carrier whenever no bunch is carried by said transfer.

3. In a cigar machine having a bunch wrapping mechanism, a transfer for transferring cigars from said wrapping mechanism, and bunch forming mechanism, a transfer device for transferring bunches to said wrapping mechanism, a wrapper carrier, a device for feeding wrappers to said carrier, control mechanism for incapacitating said device and preventing feed of wrappers to said carrier whenever no bunch is carried by said transfer to said wrapping mechanism, said control mechanism comprising a trip carried by said transfer which carries bunches to said wrapping mechanism, an electric control circuit operating therewith, and means operated by said trip for closing said circuit.

4. In a cigar machine, bunch rolling mechanism, a wrapper cutting die, a wrapper carrier movable between said die and mechanism, a transfer for conveying bunches to said mechanism, means for delivering wrappers from said die to said carrier, means constructed and arranged to prevent delivery of a wrapper to said carrier whenever no bunch is carried by said transfer, said means comprising a trip arm, an electric circuit, a switch in said circuit arranged to be closed by said arm whenever no bunch is carried by said transfer, a lever controlling the movement of said delivery means, and means for locking said lever against movement.

5. In a cigar machine, rolling mechanism, a wrapper cutting die, a wrapper carrier movable between said die and mechanism, a transfer for conveying bunches to said mechanism, means for delivering wrappers from said die to said carrier, means constructed and arranged to prevent delivery of a wrapper to said carrier whenever no bunch is carried by said transfer, said means comprising a trip arm, a switch arranged to be closed by said arm whenever no bunch is carried by said transfer, a lever controlling the movement of said delivery means, a member movable to lock said lever against delivery movement, and a solenoid controlled by said switch for effecting said movement.

6. In a cigar machine, a rolling unit, a leaf sectioning device, a transfer for conveying bunches to said unit, a carrier for delivering leaf sections from said device to said unit for association with a bunch therein, mechanism for transferring leaf sections from said device to said carrier, means for swinging said carrier to and from receiving and delivery positions, a device mounted on said transfer for detecting the presence or absence of bunches in said transfer, and means projecting into the path of travel of said transfer for incapacitating said mechanism to prevent the feed of a leaf section to said carrier whenever no bunch is carried by said transfer, said means comprising an electric circuit, a shaft, an arm mounted on said shaft, switch mechanism in said circuit carried by said shaft, said device being arranged to rock said shaft and close said switch to close said circuit whenever no bunch is carried by said transfer.

HENRY H. WHEELER.
